UNITED STATES PATENT OFFICE.

GODFREY ENGEL, SR., OF BROOKLYN, NEW YORK, ASSIGNOR TO BUFFALO FOUNDRY & MACHINE CO., OF BUFFALO, NEW YORK, A CORPORATION OF NEW YORK.

ROTARY DRIER.

Application filed September 18, 1920. Serial No. 411,846.

To all whom it may concern:

Be it known that I, GODFREY ENGEL, Sr., a citizen of the United States, and a resident of Brooklyn, Kings County, and State of New York, have invented certain new and useful Improvements in Rotary Driers, of which the following is a specification.

My present invention relates particularly to driers of the rotary type, and the objects 10 of the invention are to secure a more rapid interchange of heat and to utilize to a large extent that heat which heretofore has been wasted.

Other objects are to prevent overheating 15 of the apparatus, while at the same time facilitating the interchange of heat and, as a part of the same operation, to promote the combustion at the source of the heat.

These objects I have attained by a novel 20 construction, combination and arrangement of parts, one example of which is disclosed in the accompanying drawing wherein there is illustrated in vertical sectional view, a drier made in accordance with the invention.

25 In the construction illustrated, the material under treatment is fed into the upper end of a downwardly inclined rotating drum or conveyer cylinder 1 from a hopper 2 and is collected at the discharge end of the cylinder by a chute 3, which delivers the product onto a carrying-off conveyer 4. This conveyer drum is shown as rotatably supported on suitable bearings at 5 and 6, and as driven by suitable gearing 7.

30 The heat is supplied, in the illustration, by a fuel burning furnace 8 connected by a duct 9 with the heating or furnace chamber 10 through which the drying cylinder extends.

35 In the furnace chamber above the cylinder is an air preheater shown as consisting of a series of tubes or flues 11 open at the opposite ends to the chambers 12 and 13.

40 Partitions or bridge walls 14 and 15 are shown as provided in the furnace chamber 45 for deflecting the heat products from the furnace in a circuitous path up around the cylinder and about the preheating tubes, thence down around said tubes and cylinder 50 and again up around the cylinder and tubes to the outlet flue 16 which leads to a suitable

take-off 17, which latter may be connected with a stack.

The chamber 12 is shown as open to the air at 18 to form an intake for fresh air 55 and extending within said chamber, is one end of a double ended flow reversing valve 19 pivoted at 20 and adapted to be thrown to cooperate with a partition wall 21 in the full line position shown, or to cooperate 60 with the lower wall 22, as indicated in dotted lines. In the first or full line position, one wing of this valve cuts off entrance of air to the lower set of tubes, and the other wing of the valve shuts off the exhaust flue 65 23, the lower set of tubes being left open at such a time to the chamber 24 at the discharge end of the drier cylinder. In the reverse or dotted line position, the lower wing of the valve opens up the lower set of 70 tubes to atmosphere, cuts off the tubes from the chamber 24 and opens up this chamber to the exhaust flue 23.

At the opposite end of the preheater tubes, there is provided a double winged 75 valve 25 pivoted at 26 and controlling flow between the end chamber 13 and a chamber 27 which is open to the inlet end of the cylinder.

The two valves described ordinarily stand 80 in the positions shown in full lines and they are preferably connected so as to operate in unison as by means of a rod 28 engaged with crank arms 29 and 30, attached to the respective valves. In the position referred 85 to, the circulation through the preheater will be as indicated in the solid line arrows, the air being induced at the chamber 12 into the set of tubes above the partition 21 and passing from said tubes by way of the chamber 90 13 at the opposite end of the apparatus through the lower set of tubes and into the chamber 24 at the discharge end of the conveyer. This air, which has been preheated in its circulation through the tubes, passes 95 on an upward incline through the conveyer cylinder, absorbing moisture from the material in the conveyer during such flow.

The more or less moisture-laden air discharges from the upper or entrance end of 100 the conveyer into the chamber 27, and a special feature of the invention consists in

further utilizing this air by passing the same downward through a duct or ducts 31 beneath the grate or into the combustion chamber of the furnace. This flow of combustion supporting gas may be governed by a damper 32 inserted in the upper portion of the duct or conduit 31.

By the arrangement described, it will be seen that the material in the drying cylinder 10 is subjected to the drying influence of a current of air passing over the material under treatment counter to its flow through the conveyer; that this drying air is heated to more readily absorb moisture; that such heat 15 is derived for the greater part from the waste products of the furnace, that the vapor-laden air is used to promote combustion at the furnace, and that the vapors produced from the moisture evaporated are 20 turned combined or included with the gases of combustion into heating relation to the drying chamber, wherefore a greater volume of actual heat is supplied to the drier and at a lower temperature than would be the case 25 if the gases of combustion alone were being used.

Thus, in addition to the increased heat transfer, the apparatus on account of the lower temperature at which it operates, is 20 more durable and will stand up better in actual use. The vapor charged air passing through the furnace promotes combustion and in the case of a coal fire, prevents clinkers. It also has the effect of increasing the 35 total heat while reducing the sensible heat of the gas leaving the furnace, this arising from the fact that the specific heat of the vapors is greater than of gas.

To force the drier, the dampers may be 40 shifted to the dotted line positions indicated, in which event, air will be taken into all of the preheater tubes and discharged from chamber 13 directly into chamber 27 at the entrance end of the conveyer drum, the 45 full volume of air thus heated passing through and out the discharge end of the drum up the exhaust flue 23 as indicated by the broken line arrows. In this event, air for combustion may be supplied the furnace 50 by opening a damper or dampers 33. The connection of the valves 19 and 25 enables them both to be quickly set for either of the operations described.

From the foregoing it will be evident 55 that my invention results in greater economy, efficiency and rapidity of operation than has been possible with prior methods. Furthermore, the heating is accomplished without the furnace gases ~~contacting~~ the material.

What I claim is:

1. In a drier, a conveyer for the material under treatment, a furnace for heating said conveyer, a preheater subjected to the fur-

nace heat, and means for passing a gas directly from said preheater, over the material transported by the conveyer, and then directly to the furnace and back into heat transferring relation to the conveyer. 65

2. In a drier, an inclined conveyer cylinder, a preheater, and valve means for selectively passing a drying fluid through the preheater and into either end of the inclined drying cylinder. 70

3. In a drier, a conveyer cylinder, a preheater, means for passing a drying fluid through a section of the preheater and back through another section of the same into one end of the cylinder, and means for selectively passing the entire flow of gas in one direction through the preheater and into the opposite end of the cylinder. 75 80

4. In apparatus of the character described, a drying cylinder, a furnace for heating the same, an air preheater disposed in the path of the furnace gases, a conduit for passing air through the preheater and the drying cylinder to the furnace, valve mechanism for controlling such flow of air and including a valve at one end of the preheater for controlling flow through one section of or through the entire preheater, and a valve at the opposite end of the preheater for enforcing flow through another section of the preheater or permitting flow direct to the drying cylinder. 90 95

5. In a drier, a conveyer for the material under treatment, a furnace for heating said conveyer, a preheater subjected to the heat from the furnace, means for passing a gas through the preheater over the material transported by the conveyer to the furnace, to cause said vapor-laden air to promote combustion and add to the sensible heat of the furnace and means for returning said preheated and vapor-laden air with the products of combustion from the furnace back into heat transferring relation to the conveyer and to the preheater. 100 105 110

6. In a drier, a furnace, a conveyer for the material heated by said furnace and closed against the furnace gases, a preheater and means for supplying air to the furnace through said preheater and through the conveyer to cause the air after being preheated to pick up moisture from the material in the conveyer and for then passing the heated moisture-laden air combined with the furnace gases from the furnace into heating relation with the conveyer and preheater. 115 120

7. In a drier, a conveyer, a furnace for heating the same, a preheater subjected to the furnace heat and means for passing a drying and combustion supporting gas either through the preheater and conveyer to the furnace or simply through the preheater and conveyer. 125

8. In a drier, a conveyer, a furnace for

heating the same, a preheater subjected to the furnace heat and means for passing a drying and combustion supporting gas either through the preheater and conveyer to the 5 furnace or simply through the preheater and conveyer, said means including interconnected valves at opposite ends of the preheater.

9. In a drier, a conveyer, a preheater, means for passing a drying fluid to a section 10 of the preheater and back through another

section of the same into heat transferring relation to one end of the conveyer and means for selectively passing the entire flow of drying fluid in one direction through the preheater and into heat transferring relation to the opposite end of the conveyer. 15

In witness whereof, I have hereunto set my hand this 8th day of September, 1920.

GODFREY ENGEL, Sr.
